FIG. 2

INVENTOR.
David A. Carden
BY
Hardway Gathen
ATTORNEY.

UNITED STATES PATENT OFFICE.

DAVID A. CARDEN, OF HOUSTON, TEXAS.

DETACHABLE DRILL-BIT.

1,222,845.

Specification of Letters Patent. Patented Apr. 17, 1917.

Application filed March 23, 1916. Serial No. 86,147.

To all whom it may concern:

Be it known that I, DAVID A. CARDEN, a citizen of the United States, residing at Houston, in the county of Harris and State 5 of Texas, have invented certain new and useful improvements in Detachable Drill-Bits, of which the following is a specification.

This invention relates to new and useful improvements in a detachable drill bit.

10 The object of the invention is to provide a drill bit of the character described which may be readily attached to and detached from the lower end of the drill stem. At the present time in drilling deep wells by the 15 rotary process, a drill bit is attached to the lower end of the drill stem, or drill pipe, and said stem is then rotated by a rotary machine. When the bit becomes worn and dull the entire stem must be withdrawn in 20 order to detach the bit and replace a new one. This operation requires considerable labor and consumes much time and the object of the present invention is to provide a bit which can be detached from and replaced 25 on the lower end of the stem in the bore without withdrawing said stem.

With the above and other objects in view the invention has particular relation to certain novel features of construction, operation 30 and arrangement of parts, an example of which is given in this specification, and illustrated in the accompanying drawings, wherein:

35 Figure 1 is a vertical sectional view of the bit attached to the lower end of the drill stem,

Fig. 2 is a transverse sectional view of the bit taken on the line 2—2 of Fig. 1,

40 Fig. 3 is a vertical sectional view of the fishing tool for withdrawing the bit,

Fig. 4 is a transverse sectional view thereof taken on the line 4—4 of Fig. 1, and

Fig. 5 is a plan view of the link employed.

45 Referring now more particularly to the drawings wherein like numerals of reference designate similar parts, in each of the figures the numeral 1 refers to a drill stem or pipe having the collar 2 threaded onto the lower end thereof and forming an extension of said stem. Fitted within the lower end of the stem is a cylindrical block 3, whose lower end has an internally threaded socket to receive the externally threaded shank 4 of the drill bit 5. This block has a transverse slot 55 6 cut therethrough in which is pivoted a rela-

tively thick reamer plate 7. This reamer is pivoted in the block by means of a pin 8 extending through said block and reamer at an eccentric point. The reamer, when the bit is in operation, extends in a transverse 60 position relative to the block and is equal in length to the length of the slot 6 and is so pivoted that it may be swung around, as hereinafter explained, into a lengthwise position relative to the block 3 and when in 65 said position will fit snugly within the slot 6, the width of said reamer being the same as the thickness of the block. The lower end of the collar 2 has oppositely arranged notches 9, 9, into which the corresponding 70 ends of the reamer 7 fit when the drill is in position to operate, thus preventing the relative rotation of the stem and bit.

A sucker rod 10 is provided, which passes down through the block 3, the upper end of the block being hollowed out for this purpose, and pivoted to the lower end of said rod at their upper ends are the links 11, 11, whose lower ends are pivoted to the reamer 7, on each side, at a point diametrically opposite the pin 8. When it is desired to detach the bit from the stem, said stem is first elevated a short distance and an upward pull is then exerted, by a fishing tool hereinafter described, on the rod 10, which causes the reamer 7 to swing around on the pin 8 and rest within the slot 6 and a further pull on said rod will elevate said rod and bit and withdraw them from the stem. When it is desired to release the bit, the 90 same may be lowered until the bit 5 rests upon the bottom of the bore and the weight of the sucker rod will cause the reamer to assume a transverse position. The stem may then be lowered until it rests upon said 95 reamer and slowly turned until the notches 9, 9, are in position above the respective ends of the reamer and the stem will then, suddenly drop into the position shown in Fig. 1.

For the purpose of admitting water to the 100 point of the bit to carry away the cuttings, the water passageways 12, 12, extend down through the block 3 from its upper end and continue through the bit 5 terminating on opposite sides of the bit and the water 105 forced down through the drill stem will thus be permitted to reach the point of the bit and will carry the cuttings from said bit up through the bore on the outside of the 110 stem to the surface.

The upper end of the sucker rod has a conical shaped head 13 and spaced underneath the same is a collar 14.

For the purpose of withdrawing the bit 5 I have provided a fishing tool, shown in Figs. 3 and 4, which will now be described:— The numeral 15 refers to a pipe section, threaded into the upper end of which is the block 16, which carries an eye 17, to 10 which a cable may be attached for suspending said tool into and withdrawing it from the stem. Secured in the lower end of the pipe section 15 is a seat 18 having a central opening 19 therethrough, the upper and 15 lower ends of which are gradually enlarged forming inclined faces. Above this seat and secured to opposite sides of the section 15 are the oblong vertical bearings 20, 20, in which operate the links 21, 21. 20 When it is desired to lower the bit in the well, the fishing tool is engaged to the upper end of the sucker rod 10, as shown in Fig. 3, the lower ends of the links 21, 21, engaging underneath the head 13. The bit 25 and fishing tool sustaining the same are thus lowered into the stem by means of a cable (not shown) attached to the eye 17. When the bit has reached the bottom of the bore the lower ends of the links will contact 30 against the upper face of the collar 14, which is convex and will be by it forced apart into the corresponding recesses 22, 22, in the upper side of the seat 18 and will, by said recesses, be held against engaging 35 under the head 13 when the fishing tool is withdrawn. When it is desired to withdraw the bit, the pins 23, 23 are inserted through the corresponding orifices so that their inner ends will project into the corresponding 40 recesses 22, 22. The fishing tool is then lowered and passes down over the head 13, which, on account of its conical shape, forces the lower ends of the links 21, 21 apart, but when said head is passed above the lower 45 ends of the links, said links will engage under said head, being prevented from seating in the recesses 22, 22 by said pins and when the fishing tool is elevated the bit will be withdrawn in the manner hereinbefore explained. 50

What I claim is:

1. A device of the character described including a supporting block, a bit secured thereto, a member pivoted to the block and 55 whose ends project out laterally and seat in

corresponding notches in the lower end of the drill stem.

2. A device of the character described including a supporting block adapted to be inserted in a drill stem, a drill bit secured thereto, a member pivoted to the block whose ends project out laterally beyond said block and seat in alined notches in the lower end of the drill stem. 60

3. In a device of the character described the combination with a drill stem having oppositely arranged notches in its lower end, of a supporting block having a transverse slot therethrough, a member pivoted to said block and operating in said slot, the ends of said member normally projecting laterally beyond the block and resting in said notches, means whereby said member may be rotated on its pivotal support and thereby withdrawn within said slot. 65

4. In a device of the character described, the combination with a drill stem having oppositely arranged notches in its lower end, of a supporting block adapted to be inserted within said stem and having a slot 80 therethrough, a drill bit carried by said supporting block, a member extending transversely through said slot and pivoted eccentrically therein, the ends of said member projecting beyond said block and being received by said notches and means attached to said member whereby it may be rotated on its pivotal support. 85

5. A device of the character described including a drill stem having oppositely arranged notches in its lower end, a supporting block having a transverse slot therethrough, a bit carried by said block, a member normally extending transversely through said slot and whose ends project laterally beyond the block when in said transverse position and are received by said notches, said member being pivoted eccentrically in said slot, means attached to said member whereby it may be rotated on its pivotal support and a fishing tool arranged to engage with said means to withdraw said device through said drill stem. 90

In testimony whereof I have signed my name to this specification in the presence of 105 two subscribing witnesses.

DAVID A. CARDEN.
